Primary Examiner—Doris V. Coles*Attorney, Agent, or Firm*—Harry A. Pacini; Stephen M. Westbrook[57] **CLAIM**

The ornamental design for an insect bait station, as described and shown.

DESCRIPTION

FIG. 1 is a perspective view of an insect bait station showing our new design with a cover in place;

FIG. 2 is a perspective view of an insect bait station of FIG. 1 showing our new design with the cover removed;

FIG. 3 is a front elevational view, the sides and the back side being mirror images thereof;

FIG. 4 is a top plan view of the bait station of FIG. 2;

FIG. 5 is a bottom plan view of the bait station of FIG. 2;

FIG. 6 is a perspective view of an alternative embodiment of our new design with a cover in place;

FIG. 7 is a perspective view of an alternative embodiment of our new design of FIG. 6 with the cover removed;

FIG. 8 is a side elevational view of an alternative embodiment thereof;

FIG. 9 is a top plan view of an alternative embodiment of the bait station of FIG. 7; and,

FIG. 10 is a bottom plan view of an alternative embodiment of the bait station of FIG. 7.
